PAINT BUCKET HOLDER

Eugene Pelletier, Detroit, Mich.

Application April 10, 1950, Serial No. 154,920

6 Claims. (Cl. 248—211)

1

The present invention relates to a paint bucket holder.

It is an object of the present invention to provide a paint bucket holder adapted to support a paint bucket from a ladder.

It is a further object of the present invention to provide a paint bucket holder adapted to engage over a step of the ladder and simultaneously to engage over a side rail of the ladder so as to support the bucket rigidly in desired position.

It is a further object of the present invention to provide a paint bucket holder including a hook member engageable with both a step and side rail of the step ladder and a releasable clamping device including an inner and outer clamp adapted respectively to engage the inside of a paint bucket beneath its inwardly extending lip and the outside of the bucket.

It is a further object of the present invention to provide a paint bucket holder comprising a hook adapted to engage a step and side rail of a step ladder, and a bucket clamping device including a pair of clamps pivoted together and adapted to clamp a side wall of a paint bucket therebetween.

Other objects and features of the invention will become apparent as the description proceeds, especially when taken in conjunction with the accompanying drawings, wherein:

Figure 1 is a fragmentary perspective view showing one embodiment of the present invention.

Figure 2 is a side elevation of the bucket clamping device.

Figure 3 is a fragmentary sectional view on the line 3—3, Figure 5.

Figure 4 is a fragmentary perspective view of a second embodiment of the present invention.

Figure 5 is a side elevation of the paint bucket holder shown in Figure 4.

Figure 6 is a fragmentary side view taken on the line 6—6, Figure 5.

Referring now to the drawings, the paint bucket holder illustrated in Figure 1 comprises a support member 10 having a hook portion 12 adapted to engage over a rung 14 of the step ladder. The support 10 also comprises an inner abutment portion 16 adapted to engage the inner surface of a side rail 18 of the step ladder, a front abutment portion 20 adapted to engage the front surface 22 of the side rail 18, an outer abutment portion 24 adapted to engage the outer surface of the side rail 18, and a reversely bent support bar 26. The construction so far defined

2

provides means for holding the support bar 26 rigidly in position spaced outwardly from the side rail 18 of the step ladder.

Connected to the supporting bar 26 is a clamping device comprising an inner clamp 30. The inner clamp 30 has spaced vertical legs 32 terminating at their upper ends in eyes 34 by means of which the inner clamp is pivoted to the support bar 26. Adjacent the lower end of the legs 32, the legs are formed to extend outwardly as indicated at 36 so as to overlie the lip 38 of a paint bucket 40. The outwardly extending portions 36 are reversely bent to provide inwardly extending portions 42 which will underlie the lip 38 and these in turn are connected by a curved cross piece 44 shaped to conform generally to the curvature of the side walls of the bucket.

An outer clamp indicated generally at 50 is provided comprising spaced vertical legs 52 terminating at their upper ends in eyes 54 by means of which the outer clamp is pivoted to the support bar 26. The lower ends of the legs 52 are interconnected by a curved cross piece 56, the curvature of which conforms generally to the curvature of the paint bucket 40.

The inner clamp is provided with a cross bar 58 spanning its legs 32 and rigidly connected thereto. The outer clamp 50 is provided with a cross bar 60 spanning its legs 52 and permanently connected thereto. Means are provided for retaining the cross bars 60 and 58 in confronting position as illustrated in Figure 1 and this means comprises a screw or bolt 62 adapted to extend through an opening 64 in the clamp 30 and to cooperate with a threaded recess 66 in the clamp 50.

Referring now to Figure 4, there is illustrated a second embodiment of the invention which is identical with that previously described except for the construction of the support 70. In this case the support is adapted for use with a step ladder of the type having flat steps 72 rather than the cylindrical rungs 14 illustrated in Figure 1. In this case the support 70 includes a depending hook portion 74 adapted to engage over the back of a step 72. Extending forwardly from the hook portion 74 is an inner abutment portion 76 adapted to rest on the upper surface of the step 72 and also to engage the inner surface of the side rail 18 of the step ladder. Depending from the forward end of the abutment portion 76 is a vertical portion 80 which in turn connects with an outwardly extending front abutment portion 82 adapted to rest against the front

surface 34 of the rail 78. The support also includes an outer abutment portion 86, adapted to engage the outer surface of side rail 78, and a reversely bent forwardly extending supporting bar 88 which is similar to the bar 26 of the embodiment illustrated in Figure 1. The inner and outer clamps 30 and 50 which are suspended from the bar 88, are identical with the clamps similarly identified in Figure 1 and like reference numerals are applied thereto.

It will be observed that the clamping device affords a very firm support for the paint bucket and retains it in proper position for use. The cross pieces 44 and 56 of the clamps are curved to conform generally to the transverse curvature of the side walls of the bucket. Moreover, the cross piece 56, and due to the substantially greater length of the legs 52, engages the bucket well below its top and adds greatly to the stability of its support.

Clamps 30 and 50 are connected to the support bars 26 or 88 in such a manner as to urge the front support portions 29 or 82 of the supports into firm engagement with the front surfaces 22 or 34 respectively of the side rails of the ladder. The arrangement is such that the entire construction is substantially rigidly supported, the bucket itself tending to pivot about the axis of the support bar 26 or 88 and thus to remain in contact with the side of the ladder.

The clamping devices engage the paint bucket to hold the same firmly in position while at the same time they provide substantially no interference with free access to the interior of the bucket. Thus the painter may use the bucket as in the usual manner and may employ the inwardly extending lip of the bucket for wiping excess paint from the brush.

Clamps 30 and 50 may conveniently and economically be made from wire, and the support member 10 may also be made of an appropriate size of heavy wire, or bar stock, sufficiently strong to sustain the expected loads.

The construction is simple, cheap to manufacture, and durable in use.

While reference is made to the device as a paint bucket holder, it is obvious that it is applicable to hold any type of bucket or can which is provided with an inwardly extending lip at its upper surface.

The drawings and the foregoing specification constitute a description of the improved paint bucket holder in such full, clear, concise and exact terms as to enable any person skilled in the art to practice the invention, the scope of which is indicated by the appended claims.

What I claim as my invention is:

1. In a bucket holder, a hook engageable over a step of a ladder and including a portion extending outside one of the side members of the ladder, a support bar on said portion, and a pair of clamping members pivoted to said support bar, said clamping members comprising an inner member having depending legs each terminating in a hook engageable over the lip of a bucket, and a cross-member at the bottom of said legs curved to fit beneath the bucket lip.

2. A holder as defined in claim 1, said clamping members comprising an outer member having depending legs considerably longer than the legs of said inner member, and a cross-member at the bottom of said legs curved to conform to the exterior of a bucket.

3. A bucket holder comprising a support having portions shaped to engage over a step and side member of a step ladder and including a horizontal bar spaced laterally from the side member of the ladder, an inner clamp formed of wire having spaced vertical legs, eyes at the upper end of said legs pivoted to said bar, and a curved cross piece connecting the lower ends of said legs adapted to extend beneath the lip of a bucket, an outer clamp formed of wire having spaced vertical legs, eyes at the upper end of said legs pivoted to said bar, and a curved cross piece connecting the lower ends of said legs curved to conform to the outer surface of a bucket.

4. A holder as defined in claim 3 in which the legs of the outer clamp are substantially longer than those of the inner clamp to position its cross piece substantially below the top of the bucket.

5. A holder as defined in claim 4 including a cross bar connected between the legs of each of said clamps adapted to register when said clamps are in closed position, and locking means interconnecting said bars to hold said clamps in closed position.

6. A holder as defined in claim 5, said locking means comprising a screw carried by one of said bars and a tapped opening in the other member.

EUGENE PELLETIER.
